UNITED STATES PATENT OFFICE.

JAMES DAVID HARP, OF MODESTO, CALIFORNIA.

MOTOR-VEHICLE.

SPECIFICATION forming part of Letters Patent No. 729,579, dated June 2, 1903.

Application filed July 5, 1902. Serial No. 114,495. (No model.)

To all whom it may concern:

Be it known that I, JAMES DAVID HARP, a citizen of the United States, and a resident of Modesto, in the county of Stanislaus and State 5 of California, have invented a new and Improved Motor-Vehicle, of which the following is a full, clear, and exact description.

My invention relates to motor-vehicles, my object more particularly being to provide a 10 turning-gear upon the axle to which the power is applied for the purpose of propelling the machine.

Reference is to be had to the accompanying drawings, forming a part of this specification, 15 in which similar characters of reference indicate corresponding parts in all the figures.

Figure 1 is a side elevation showing my invention as applied to a motor-vehicle. Fig. 2 is a front elevation of the same, and Fig. 3 20 is a vertical central section through one of the front wheels.

The body 1 of the vehicle is mounted upon a subframe 2 substantially in the usual manner and is provided with rear wheels 3 and 25 front wheels 4 and 5. A pair of revoluble stems 6 7 are provided with forks 8 9, which span the wheels 4 5, these forks being supported upon a cross-brace 13, provided with a bearing 12, through which passes a revolu- 30 ble steering-post 10, the lower end of which is mounted in a bearing 11 upon the subframe resting upon the brackets 16 of the framework 17. The cross-brace 13 is rigidly mounted upon vertical braces 14 15, which 35 are in turn supported by the subframe, to which their lower ends are secured.

Upon the revoluble stems 6 7 are mounted cranks 20, provided with integral heads 18 19. The outer or free ends of the cranks 20 40 are connected with a cross-pitman 21, the center of which is pivotally secured to an arm 25, the ends being secured to the outer free ends of the cranks 20 by means of nuts 23 24.

The steering-post 10 is provided with an 45 arm 26; this arm being in turn provided with a handle 27; the last-mentioned two elements constituting a steering-lever of the ordinary type. The arrangement of the parts above described is such that a chauffeur by manipu- 50 lating the handle 27 and thereby moving the arm 26 radially is enabled to rock each of the stems 6 7 to the right or left within

certain limits, thereby causing the forks 8 9 to alter the respective planes of the wheels 4 and 5 relatively to the general position of the 55 vehicle-body.

A sprocket-wheel 28 is rigidly mounted on the center of the revolving driving-axle, which in this instance is the front axle. A sprocket-chain 29 actuates the sprocket-wheel 60 in the usual manner.

The revoluble driving-axle is a composite structure, parts of which are flexibly connected together, as hereinafter explained. The central longitudinal portion 30 of the 65 driving-axle is mounted within bearings 31 32 and is free to revolve therein when rotated by the sprocket-wheel 28. Mounted rigidly upon the longitudinal member 30 is a globe-spindle 33, provided with a set-screw 34 or 70 equivalent device, whereby said globe-spindle is detachably but rigidly secured upon the member 30, so as to be revoluble therewith.

Short cylindrical spindles 35 constitute the end portions or members of the driving-axle. 75 These end portions are connected, by means of universal joints 36, with the central or middle member 30 and are revoluble therewith, but are free to move radially for the purpose of enabling the wheels to turn in planes independent of the general vertical plane of the vehicle.

The globe-spindles 33 are provided with mutilations 37 for enabling the end members 35 of the axle to move radially upon the universal joints 36. Each end member 35 is provided with a washer 39 and also with a slip-key 38, whereby it is firmly secured to the globe 43, and with a washer 39. The lower ends of the forks 8 9 are provided, respectively, with annular bearings 40 47, the bearing 47 being considerably larger than the bearing 40. A nut 41 is secured upon the extreme outer end of each of the end members 35. 95

The spokes of the wheel are shown at 42 and are mounted upon a globe-hub 43. A quarter-globe 44 is fitted into the globe-hub, as indicated in Fig. 3, and is secured in position by means of screws 45 46. The globe-hub has the general shape of a dome, as indicated in Fig. 3, and with the quarter-globe 44 in position its interior is substantially spherical. The quarter-globe 44 is pro- 100

vided with mutilations 49 for the purpose of allowing the globe-hub to move in divers radial directions over the globe-spindle 33. The large end of the dome-shaped globe-hub is 5 provided with an annular channel 48, within which rests the large annular bearing 47. The springs 50 51 are of the usual pattern.

It will be noted that the globe-hub 43, provided with the quarter-globe 44, when fitted 10 upon the spindle 33 forms a type of ball-and-socket joint, which aside from the controlling action of the fork 8 or 9 allows the wheel to turn in almost any plane desired. Normally the forks 8 9 are held in the position indicated 15 in Figs. 1 and 2. By moving the handle 27 to the right or left, however, the globe-hubs are turned accordingly, so that the position of each of the front wheels is changed into a different vertical plane. The weight 20 of the front portion of the vehicle rests directly upon the middle section 30 of the driving-axle and is thence transferred, by means of the globe-spindles 33, directly into the plane passing through the respective 25 centers of the front wheels. There is therefore no tendency of the front axle to buckle, whatever may be the position of the front wheels or whatever may be the degree of weight resting thereon. The ball-and-socket joint 30 occupying the center of each of the front 30 wheels is a turning device pure and simple. It does not affect the distribution of the weight upon the front wheels.

Having thus described my invention, I 35 claim as new and desire to secure by Letters Patent—

1. A motor-vehicle comprising a revoluble axle, built up by a plurality of longitudinal parts connected together by complete universal joints, a globe-spindle rigidly connected 40 with one of said parts and partially incasing one of said universal joints, a wheel provided with a globe-hub, said hub being rigidly secured upon another of said longitudinal parts 45 and also journaled upon said globe-spindle, a

steering-fork straddling said wheel and provided with separate bearings mounted respectively upon one of said longitudinal parts and upon said globe-hub, and means controllable at will for turning said fork. 50

2. A motor-vehicle comprising a frame, a revoluble axle consisting of a central longitudinal member provided with a sprocket-wheel for communicating rotary motion thereto, longitudinal end members connected with 55 said central member by means of universal joints, globe-spindles mounted rigidly upon said central member and partially incasing said universal joints, wheels provided with globe-hubs, said hubs being rigidly secured 60 upon said end members and journaled upon said globe-spindles, and forks pivotally mounted within said frame and journaled upon said end members and said globe-hubs.

3. A motor-vehicle, comprising a frame, a 65 revoluble axle consisting of a central longitudinal member provided with a sprocket-wheel for communicating rotary motion thereto, longitudinal end members connected with 70 said central member by means of universal joints, globe-spindles mounted rigidly upon said central member, and partially incasing said universal joints, wheels provided with globe-hubs, each hub being surrounded by an annular bearing-channel and keyed directly 75 upon one of said end members so as to form a rigid connection therewith, forks pivotally mounted upon said frame and provided with annular bearings for engaging said end members and said annular bearing-channels, 80 and means controllable at will for rocking said forks and thereby steering the vehicle.

In testimony whereof I have signed my name to this specification in the presence of two subscribing witnesses.

JAMES DAVID HARP.
